(57) **CLAIM**

The ornamental design for a shielded spinal stabilization plate, as shown and described.

DESCRIPTION

FIG. 1 is a top perspective view of a shielded spinal stabilization plate with both sides in open positions showing our new design;

FIG. 2 is a top plan view thereof;

FIG. 3 is a side elevation thereof;

FIG. 4 is an end elevation thereof;

FIG. 5 is a bottom plan view thereof;

FIG. 6 is a top perspective view thereof with one shield in an open position and one shield in a closed position;

FIG. 7 is a top plan view thereof;

FIG. 8 is a side elevation thereof;

FIG. 9 is a left end elevation thereof;

FIG. 10 is a right end elevation thereof;

FIG. 11 is a bottom plan view thereof;

FIG. 12 is a top perspective view thereof with both shields in closed positions;

FIG. 13 is a top plan view thereof;

FIG. 14 is a side elevation thereof;

FIG. 15 is an end elevation thereof; and,

FIG. 16 is a bottom plan view thereof.
